REFLECTOR HOUSING FOR AN AUTOMOBILE FENDER

Carl W. Hood, Detroit, Mich., assignor to Chrysler
Corporation, Highland Park, Mich., a corpora-
tion of Delaware

Application May 20, 1950, Serial No. 10,059

Term of patent 7 years

(Cl. D14—6)

To all whom it may concern:

Be it known that I, Carl W. Hood, a citizen of the United States, residing in the city of Detroit, county of Wayne, and State of Michigan, have invented a new, original, and ornamental Design for a Reflector Housing for an Automobile Fender, of which the following is a specification, reference being had to the accompanying drawing, forming part thereof, in which:

Fig. 1 is a front elevational view of a reflector housing for an automobile fender showing my new design;

Fig. 2 is a top plan view thereof;

Fig. 3 is a side elevational view thereof;

Fig. 4 is an elevational view showing the side opposite to Fig. 3;

Fig. 5 is a cross sectional view taken on the line 5—5 of Fig. 1; and

Fig. 6 is a perspective view of a reflector housing for an automobile fender of my invention, the broken line showing therein of a portion of an automobile being for illustrative purposes only.

I claim:

The ornamental design for a reflector housing for an automobile fender, substantially as shown and described.

CARL W. HOOD.
